UNITED STATES PATENT OFFICE.

JOHN LE VALLEY, OF PAINTED POST, NEW YORK, ASSIGNOR TO INGERSOLL-RAND COMPANY, OF JERSEY CITY, NEW JERSEY, A CORPORATION OF NEW JERSEY.

UNLOADING VALVE.

Application filed November 24, 1926. Serial No. 150,473.

This invention relates to compressors, but more particularly to an unloading valve for compressors of the multi-cylinder type.

The objects of the invention are to unload 5 the cylinders whenever the receiver pressure reaches a certain predetermined value and to produce a compact and simplified unloading mechanism which requires only a few simple parts and which may be easily operated and 10 cheaply maintained. These objects are accomplished in the present instance by a reciprocable valve disposed in the wall between the cylinder chambers to control the 15 passage through which communication between the cylinder chambers may be established.

Other objects will be in part obvious and in part pointed out hereinafter.

The invention consists of the combination 20 of elements and features of construction substantially as hereinafter described and more particularly pointed out in the appended claims and illustrated in the accompanying drawing, in which is illustrated a sectional 25 elevation of so much of a compressor as will serve to illustrate the invention.

Referring more particularly to the drawing, A designates a cylinder having in this instance a pair of cylinder chambers B. 30 Pistons C reciprocable in the cylinder chambers B are provided with connecting rods D which may be operatively connected to a suitable prime mover (not shown).

Supported by the cylinder A is a head E 35 having a chamber F which communicates with a receiver tank G through a conduit H. The head E may be secured to the cylinder A in any suitable manner. In the present instance bolts J are indicated for that purpose.

In an inner wall K of the valve box E are seated discharge valves L of a well known type for controlling the exhaust of pressure fluid from the cylinder chambers B 45 into the chamber F.

In accordance with the present invention, a passage O is formed through a wall P between the cylinder chambers B, preferably near the discharge end of the cylinder chambers and in this instance is intersected by a longitudinal bore Q in the wall P.

Disposed in the bore Q is a valve R having end heads S and T which cooperate slidably with the bore Q. The heads S and T are 55 connected by a stem U and the head S car-

ries at its upper end a flange V which extends into a recess W of the valve box E. In the construction shown the flange V is adapted to seat on the bottom of the recess W for limiting downward or inward movement of the valve R in the bore Q.

To the end that the valve S may be suitably held in its closed position during the normal operation of the compressor, a spring Z is disposed in the recess W to seat with one end on the flange V of the valve R and with its other end against a cover b screwed in the end of the recess W to form a closure therefor.

Any suitable means may be provided for 70 controlling the admission of pressure fluid from the receiver tank G to the end of the bore Q. Such means consist in the present instance, of a pipe c which communicates with the bore Q through a port d. The pipe 75 c is provided with a pressure controlling valve e preferably of the type described in United States Patent No. 1,138,278 granted May 4, 1915, to J. H. Castle and W. G. Rogers. Reference may be had to this patent for a detail description of the controlling valve. However, it is to be understood that the invention is not dependent upon its successful functioning on this particular type of valve, but that any suitable device 80 may be interposed in the pipe line c or otherwise suitably connected for automatically admitting pressure fluid into the bore Q whenever the receiver pressure exceeds a value which it is desired to maintain in the 85 receiver tank G.

During the normal operation of the compressor, the air compressed in the cylinder chambers B will pass through the discharge valves L into the chamber F, thence through 90 the conduit H into the receiver tank G. As long as the receiver pressure remains below a certain predetermined value the valve R will be held closed by the spring Z. However, after the pressure in the receiver tank 95 G rises to or exceeds the predetermined pressure the valve e will function in a well understood manner to admit pressure fluid from the receiver tank G into the bore Q. Such pressure fluid acting against the lower 100 or inner end of the valve R will overcome the pressure exerted by the spring Z and will raise the valve R until the valve head S uncovers the passage O. In this way the cylinder chambers B will be short-circuited 105 110

so that any air existing in the cylinder chambers B will be discharged through the passage O and around the valve stem U from one chamber B to the other chamber. The pistons C will then reciprocate in the chambers B without doing any actual work of compression.

After the receiver pressure has been sufficiently decreased to allow the controlling 10 valve e to close, the supply of pressure fluid to the bore Q will be cut off and any pressure fluid existing in said bore will be exhausted therefrom through the pipe c and through the valve e in the usual manner, 15 thus permitting the spring Z to return the valve R to its seat and cut off communication between the cylinder chambers B.

The present invention has been found to be particularly desirable in compressors of 20 the portable type for the reason that it may be applied to a multi-cylinder compressor without materially increasing the weight thereof. The device is compact and of simple construction. It may be readily installed 25 in the compressor and is capable of rendering service for a long period of time without requiring frequent inspection and adjustment. Another desirable feature of the present invention is that the unloading valve 30 is completely housed within the compressor casing, thus eliminating any objectionable

projections which may become disarranged or broken due to the rough usage which machines of this type frequently receive.

I claim:

1. In a compressor having a plurality of cylinder chambers, a common wall between the chambers having a passage to establish communication between the chambers, said wall having a longitudinal bore intersecting 40 the passage, and a valve in the bore exposed at one end to storage pressure whereby it is actuated for establishing communication between the chambers whenever the storage pressure reaches a certain predetermined 45 value.

2. In a compressor having a plurality of cylinder chambers, a common wall between the chambers having a passage for establishing communication between the chambers, said wall also having a longitudinal bore intersecting the passage, a valve reciprocable in the bore to control the passage, means for admitting pressure fluid from a receiver to the bore for opening the valve whenever 50 the pressure in such receiver rises to a certain predetermined value, and a spring normally holding said valve closed.

In testimony whereof I have signed this specification.

JOHN LE VALLEY.
